UNITED STATES PATENT OFFICE.

FRIDTJOF NIELSEN BRÖNDBY, OF CHRISTIANIA, NORWAY, ASSIGNOR TO A/S PERKUSION, A BUSINESS ENTITY OF CHRISTIANIA, NORWAY.

IGNITION MECHANISM FOR HAND GRENADES, PROJECTILES, AND MINES.

1,416,662.

Specification of Letters Patent. Patented May 16, 1922.

Application filed December 31, 1918. Serial No. 269,164.

To all whom it may concern:

Be it known that I, FRIDTJOF NIELSEN BRÖNDBY, a subject of Norway, and a resident of Christiania, Kingdom of Norway, 5 have invented certain new and useful Improvements in the Ignition Mechanism for Hand Grenades, Projectiles, and Mines, for which I have filed an application in Norway July 27, 1917; and of which the following is a specification.

This invention relates to ignition mechanisms for hand grenades, projectiles and mines and the object of the invention is a mechanism which will cause ignition of the 15 explosive charge of the projectile in question independent of the position of the projectile on striking the ground or other object.

My ignition mechanism broadly consists 20 of an ignition piston and a rod at one end provided with a head and pivoted at the other end in a manner to be capable of making oscillations of a pendulum in all directions and of sliding towards the ignition piston in its longitudinal direction. In 25 the normal position the end of the rod almost touches the end of the ignition piston. These ends are preferably both concave and are connected by an intermediate link such 30 as a ball or similar object.

The rod is further provided with a slide- 35 able weight which is pressed against the head of the rod and is kept in this position by means of a spring which however in its normal position has no operative tension. If the grenade or projectile strikes with its 40 head first the slideable weight will press the rod towards the ignition piston and this will ignite the charge. If striking takes place

45 with the other end first the slideable weight will compress the spring which on recoiling will force the weight forwardly again to press the rod toward the ignition piston and ignition will take place. If side striking 50 takes place the rod will act as a pendulum, the weight pressing the pendulum to one side. The concave ends of the rod and the ignition piston in connection with the intermediate link will then act as a wedge and move the ignition piston to cause ignition.

55 My ignition mechanism is further provided with a safety device in order to prevent premature ignition. This safety device preferably consists of a pin, one end of which in normal position is pressed into a groove in

the head of the ignition piston and thus prevents the latter from moving, the other end of the pin being held in position by a stop. Until this stop is removed the pin cannot leave the groove in the ignition piston and consequently no ignition can take place.

In the accompanying drawing forming part of this application a specific example of my invention is illustrated.

Figure 1 is a longitudinal central section of the invention embodied in a hand grenade.

Fig. 2 is a similar section broken away and illustrating the adaptation of the invention to a projectile to be fired from the end 70 of a rifle.

The ignition piston 10 is provided with a groove 1 and is normally held in position by the pin 11, one end of which normally extends into the groove. The piston is further 75 provided with a spring 12. A steel ball 18 forms the intermediate link between the concave ends of the ignition piston and the rod or ignition hammer 4. This rod 4 is provided with a weight 3 which may 80 slide along the rod and which is normally held in position tight to the head of the rod by the spring 5. The rear end of the rod 4 is pivoted at the rear portion of the grenade body 7. This pivoting is effected by the end of the rod being inserted in a well 15 there located.

The pin 11 is normally held in the groove 1 by a stop 6 which is of resilient material and the rearward end 16 of which by reason 90 of its spring tension presses against an annular flange 17 formed on the forward end of the handle 2 of the grenade. Intermediate of the stop is an aperture 24 for subsequent registration with the pin 11.

The handle of the grenade is normally locked in a safety position with the body of the grenade by a pin 9 which must be removed before the grenade is used. A coil spring 8 surrounds the forward portion of 100 the handle and has one end abutting against the aforesaid flange and the other end against the rear of the grenade casing 13, 14.

The explosive charge 21 is carried in the forward part 13 of the said casing, within 105 which is suitably mounted a detonator 20 in explosive relation with a percussion charge 19 mounted in advance of the ignition piston 10 in a position to be detonated thereby on forward movement thereof in re- 110

spect to the fuse body. Other details of construction will be readily understood from the drawings.

In order to use the grenade I proceed as follows:

I remove the pin 9, grasp the grenade by the handle 2 and throw it. By the swinging motion of my arm the weight of the grenade will compress the spring 8. The end 16 of 10 the stop 6 will move past the flange 17 and, on account of its tension, will spring inwardly in front of the flange. When the grenade has left the hand and the spring 8 recoils the flange 17 moves the stop 6 forwardly until the aperture 24 is in registration with the pin. Thus the pin 11 will be released. This pin will however not move until the grenade strikes. Then the following cases are possible: 1: The grenade strikes 15 with the shaft up. 2: The grenade strikes with the shaft down. 3: The grenade strikes with its side. 4: The grenade strikes in an intermediate position.

In these cases my mechanism will act in 25 the following manners.

1. The impact of the weight 3 will press down the piston into the percussion cap 19 and cause ignition of the detonator 20 and the explosive charge 21.
2. The impact of the weight 3 will compress the spring 5 on the recoil of which the weight will hit the head of the rod 4 and press the piston into the percussion cap.
3. The rod 4 will act as a pendulum, the weight 3 pressing it to one side. The concave ends of the rod and the piston in connection with the steel ball 18 will then act as a wedge and press the piston into the percussion cap.
4. The piston will be pressed into the percussion cap by a combination of the above described actions.

In above specific illustration of my invention I have only described the use of my 45 ignition mechanism in a hand grenade. The ignition mechanism will however act in exactly the same manner if the grenade is used as a rifle grenade or as the projectile of a bomb thrower. I then prefer to provide the grenade with a hollow tail 22 and steering vanes 23. The tail may be temporarily attached to the barrel of a rifle or preferably may be provided with a steel tube fitting tightly inside the tail, and being attached to the rifle barrel, thus serving as a prolongation of the barrel. When firing the expanding gases will push the body of the 50 grenade forward in respect to the handle, the movement of which is retarded by inertia, compressing the spring 8 and thus moving forward the stop 6 in the same manner as when the grenade is thrown by hand.

The above described rifle grenade may further be used as a bomb in any commonly 65 used type of bomb thrower, it being possible

to vary the size of the grenade or bomb as desired.

The foregoing detailed description has been given for clearness of understanding and no undue limitation should be deduced therefrom but the appended claims should be construed as broadly as permissible in view of the prior art.

What I claim as new and desire to secure by Letters Patent of the United States is:

1. In an ignition mechanism for a fuse, the combination of a movable firing member, an actuating member therefor, the firing member and actuating member having on adjacent ends broad heads coacting with each other and the actuating member being mounted for a swinging movement around its opposite end, a weight slidably mounted on the actuating member, and a firing spring normally holding the weight against a stop on the actuating member and towards the firing member.

2. In an ignition mechanism for a fuse, the combination of a firing member movable to effect explosion of the fuse, an actuating member for effecting said movement pivotally connected with the fuse at one end, a link intermediate the firing member and actuating member, and a weight mounted in operative connection with but movable in relation to the actuating member and effective to cause a pendulum movement of the last named member whereby the firing member is caused to function.

3. Ignition mechanism for hand grenades, projectiles and mines comprising the combination of a percussion cap, an ignition piston the end of which is concave, and an ignition hammer pivoted at one end, the other end being concave and connected with the ignition piston by means of a ball which in connection with the concave ends of the ignition hammer and the ignition piston by side striking will act as a wedge and force the ignition piston into the percussion cap.

4. Ignition mechanism for hand grenades, projectiles and mines comprising the combination of a percussion cap, an ignition piston the end of which is concave, and an ignition hammer pivoted at one end and provided with a slidable weight bearing against the head of the hammer and being kept in position by a spring which when pressed down by said weight will recoil and thereby move the ignition hammer towards the ignition piston and force said piston into the percussion cap, the head of said hammer being concave and being connected with the concave end of said piston by means of a ball which in connection with said concave ends of the ignition hammer and ignition piston by side striking will act as a wedge and force said piston into the percussion cap.

5. Ignition mechanism for hand grenades,

projectiles and mines comprising the combination of a percussion cap, an ignition piston the end of which is concave, and an ignition hammer pivoted at one end and provided with a slidable weight bearing against the head of the hammer and being kept in position by a spring which when pressed down by said weight will recoil and thereby move the ignition hammer towards

- 10 the ignition piston and force said piston into the percussion cap, the head of said hammer being concave and being connected with the concave end of said piston by means of a ball which in connection with said
  - 15 concave ends of the ignition hammer and ignition piston by side striking will act as a wedge and force said piston into the percussion cap, said piston being normally held in position by a pin catching in an annular
  - 20 groove in the piston, the other end of the pin bearing against a stop which is automatically pushed aside before striking of the projectile.

25 6. Ignition mechanism for hand grenades, projectiles and mines comprising the combination of a percussion cap, an ignition piston the end of which is concave, and an ignition hammer pivoted at one end and provided with a slidable weight bearing
30 against the head of the hammer and being kept in position by a spring which when pressed down by said weight will recoil and thereby move the ignition hammer towards the ignition piston and force said piston
35 into the percussion cap, the head of said hammer being concave and being connected with the concave end of said piston by means of a ball which in connection with said

concave ends of the ignition hammer and ignition piston by side striking will act as a wedge and force said piston into the percussion cap, said piston being normally held in position by a pin with a conical end catching in an annular groove in the piston, the other end of the pin bearing against a stop which is automatically pushed aside before striking of the projectile.

7. Ignition mechanism for hand grenades, projectiles and mines comprising the combination of a percussion cap, an ignition piston the end of which is concave, and an ignition hammer pivoted at one end and provided with a slideable weight bearing against the head of the hammer and being kept in position by a spring which when pressed down by said weight will recoil and thereby move the ignition hammer towards the ignition piston and force said piston into the percussion cap, the head of said hammer being concave and being connected with the concave end of said piston by means of a ball which in connection with said concave ends of the ignition hammer and ignition piston by side striking will act as a wedge and force said piston into the percussion cap, said piston being normally held in position by a pin with a conical end catching in an annular groove in the piston, the other end of the pin bearing against a stop which is automatically pushed aside by recoil of a spring which is pressed down when the projectile is launched. 70

Signed at Christiania, Norway, on this 8th
of August, 1918.
